UNITED STATES PATENT OFFICE.

HENRY C. SMART, OF BROOKLYN, NEW YORK, ASSIGNOR TO STANDARD OIL COMPANY OF NEW YORK, OF NEW YORK, N. Y., A CORPORATION OF NEW YORK.

SEPARATING CONSTITUENT HYDROCARBONS OF PETROLEUM VAPORS BY PARTIAL CONDENSATION THEREOF.

Application filed March 25, 1919. Serial No. 284,920.

To all whom it may concern:

Be it known that I, HENRY C. SMART, a citizen of the United States, residing at New York city, borough of Brooklyn, county 5 of Kings, in the State of New York, have invented certain new and useful Improvements in Separating Constituent Hydrocarbons of Petroleum Vapors by Partial Condensation Thereof, of which the following is a specification.

This invention relates more particularly to separating constituent hydrocarbons of petroleum vapors which have been evolved at least in part at temperatures above 600° 15 F., say in distilling gas oil or other heavy distillate of petroleum under superatmospheric pressure for motor spirit (or for motor spirit and other products), or in distilling crude petroleum for naphtha, burning oil (kerosene) and heavier distillates. Such separation by partial condensation of the vapors has been recognized as possessing special difficulties in view of the character of the vapors operated upon. Each improvement is, however, to be secured also for 25 all other appropriate uses.

In the accompanying drawings Fig. 1 is a view in central vertical section of an air cooled condensing tower in accordance 30 with the invention; Fig. 2 is a side elevation partly broken away of two air cooled condensing towers connected in series, each of the towers being constructed in accordance with the invention; and Figs. 3 and 35 4 are partial views in central vertical of the two towers of Fig. 2 respectively.

Heretofore many types of air cooled condensing towers have been devised. Without here attempting to mention all it may be said 40 that in one of these old types there has been an upright shell exposed freely to the atmosphere for cooling on its exterior and provided inside with a series of deflectors which cause the vapors to pass at intervals 45 as an annular stream of large diameter and relatively small thickness between the peripheries of said deflectors and the shell wall, that in another type an upright shell this contained numerous at least approxi- 50 mately parallel pipes, which subdivide the vapors and the cooling air into numerous streams, the pipes in some towers of this type conveying the vapors and in others the cooling air, while the other aeriform fluid

(that is to say, the cooling air or the vapors, 55 according to the case) flows over and between the pipes, and that in each of the two types mentioned the condensate has ordinarily, but not in every instance, descended through the same passages through which 60 the vapors have ascended.

In accordance with the present invention, and as shown in Fig. 1, the shell *a*, of large diameter, has a vapor inlet *b* below and an outlet *d* above for the residual vapors. It is 65 provided inside with deflectors *f*, consisting each of a disk *f'* (which lies transversely to the shell wall and slopes downward towards the center) and an upright rim *f''*, and being of somewhat smaller diameter than 70 the inside of the shell *a*; so as to form a succession of annular passages *g* of large diameter and relatively small thickness. The rising vapors are thus made to pass at 75 intervals as an annular stream of large diameter and relatively small thickness between the peripheries of said deflectors and the shell wall. The supports for these deflectors can be of any suitable description 80 which allows the vapors to pass as aforesaid.

As shown in Fig. 1, the supports for deflectors *f* consist of rivets 25; each of which passes through the rim *f''* of a deflector and through the wall of shell *a*, and also through 85 an intervening washer 26. They are headed inside the rims and outside the shell wall. As shown in Fig. 3, bent supporting strips 27 are fastened to the inside of the wall of shell *a* and to the rims *f''* of the deflectors 90 at the upper parts of said rims. In Fig. 4 ties 28 and struts 29 are shown for supporting deflectors *f* through the medium of a ring *h*, itself secured to the shell wall as mentioned below. Each of the strips composing said ties and struts is fastened at one end to the ring *h* and at its opposite end to the disk *f'* of a deflector *f*.

Below each deflector *f* is a ring *h* having a large central opening; which ring lies 100 transversely to the shell wall, with which it makes a close joint at the periphery, and slopes downward toward the central opening. It is shown secured to the shell wall by means of an angle strip *i*.

Inclosing the shell *a* is a flue jacket *j*, that is to say, a jacket with an interior diameter substantially greater than the ex-

terior of the shell *a*, provided with an inlet for cooling air below (at *k*) and an outlet for the warmed air above (at *l*). A stream of cooling air will thus rise through the flue in jacket *j* when its inlet *k* and outlet *l* are open and the shell *a* is heated by vapors in the same.

The said flue is provided with means *m* for controlling the flow of air through it by opening and closing an appropriate part of said flue. As shown, the jacket *j* is brought inward over the top of shell *a*; and the warmed air outlet *l*, of smaller diameter than the shell, is located in the portion of said jacket which overlies said shell. The air flow controlling means *m* as shown consists of a disk valve movable about a horizontal axis, being mounted on the lever *n*, which is fulcrumed on a horizontal pivot on the post *p* and is operated by a chain *q*. The chain is engaged with a hook or other holding device (not shown) for retaining the valve in the position in which it is open to the extent desired. The valve *m* seats itself when closed on the structure in which the outlet *l* is located.

In operation, the vapors are cooled by contact with the wall of shell *a* (from which the heat is abstracted by the stream of cooling air in the flue of jacket *j*) and become condensed in part. Drops of condensate first form, it is believed, and then unite into a stream; which flows downward in the tower. Instead of allowing this stream to follow the same course downwardly, which is pursued upwardly by the vapors, each of the deflectors *f* is provided with an opening *r*; through which the condensate can pass; but which is closed (practically at least) against the passage of vapors in some suitable way, say by making it sufficiently small in size relatively to the annular passage *g*, or (as in Fig. 1) by providing it with a trap *s*, or as may be preferred.

The separation of condensate from residual vapors is also promoted by the downward inclination inwardly of the bottom surfaces of the rings *h*; which inclination favors the collection thereon of the drops of condensate which may be in suspension in the vapor current by placing said surfaces more directly in opposition to the vapor flow and so giving somewhat of a downward sweep to the vapors. The flow by gravitation of these drops towards the inner edge of the ring is also favored by said inclination; which is made sufficient for the purpose. The similar downward inclination inwardly of the bottom surfaces of deflectors *f* also favors the flow by gravity inward of the drops of condensate which may collect on these surfaces.

By having confined streams respectively of cooling air and vapors to be cooled which travel in the same direction on opposite sides of the shell wall *a* the temperature difference

between the fluids becomes smaller towards the respective outlets; so that the rate of cooling tends to diminish in like manner; and the escaping vapors should be the more free from entrained particles of condensate 70 for this reason.

In the new or improved condensing tower, therefore, a confined and controllable stream of cooling air rising in a flue which is formed at least in part by the shell wall and increasing in temperature as it rises abstracts heat by conduction through the intervening shell wall from a stream of vapors to be cooled, which rises in the shell *a* and diminishes in temperature as it rises, which is made to pass 80 at intervals as an annular stream of large diameter and relatively small thickness between the peripheries of deflectors *f* and the shell wall, which is separated from the descending stream of condensate (whose path 85 is through the deflectors *f* and rings *h* instead of around the same after the manner of the vapors) and which is freed as promptly as may be from the drops of condensate by special arrangements to that end (such as 90 the inclination downward and inward of the bottom surfaces of the deflectors *f* and rings *h*).

The tower of Fig. 1 is designed more particularly for use in distilling petroleum under superatmospheric pressure at decomposing temperatures in the oil operated upon (all of which temperatures lie above 600° F.). The compressed vapors would pass through the vapor pipe *c* from the pressure 95 still (not shown) to the vapor inlet *b* of the tower; and the residual vapors, still compressed, would pass by pipe *t* to a water cooled condenser (not shown). The condensate would pass away from the tower by the 105 pipe *u*. Whatever liquid may separate from the vapors in vapor pipe *c* would return to the still, the vapor pipe *c* inclining upward towards the tower. The condensate from the tower could be delivered by pipe *u* to a 110 distillate receiver or to the still, as the operator might determine. By closing the valve *v* in pipe *u* the condensate from the tower could be made to return to the pressure still through the vapor pipe *c*. It is 115 designed for the operator to adjust the valve *m* so as to obtain condensates of the character desired by him from the tower (which is shown) and from the water cooled condenser (not shown) which is connected with pipe 120 *t*. A tower with a shell *a* three and a half feet in diameter and twenty five feet in height, containing six of the deflectors *f* is considered of suitable size for a pressure still in the form of a horizontal cylinder ten feet 125 in diameter by forty feet in length, the vapor pipe *c* to be six inches in diameter. The annular passages *g* in such a tower may be say one inch in width between the rims *f* of deflectors *f* and the enclosing shell *a*.

The towers of Figs. 2, 3 and 4 are designed more particularly for use in distilling crude petroleum at temperatures in the oil operated upon which rise to above 600° F. 5 after the naturally present burning oil (kerosene) hydrocarbons have come over. In each of these towers the similarly lettered parts correspond with those of Fig. 1. It will be observed that the rims f'' of 10 the deflectors f are lowest in proportion to diameter in Fig. 3, highest in Fig. 1 and intermediate in Fig. 4. The ratio of depth of rim to diameter of deflector might be less than the minimum or more than the 15 maximum shown. Rims might even be omitted from all or from part of the deflectors, if preferred. It is considered not worth while to provide traps for the openings in the bottoms of deflectors f in the towers of 20 Figs. 2, 3 and 4, in view of the intention to operate them under atmospheric pressure.

Two of the deflectors w in the lower part 25 of shell a in the large tower of Figs. 2 and 3 are directly connected with pipes 12 and 13 for withdrawal of condensate; and there 30 is also a condensate withdrawing pipe 14 leading from the bottom of the shell a . The condensate from all or any of these pipes can be returned to the still or be drawn off 35 as distillate. Appropriate arrangements could be made for receiving last runnings in a distillation to dryness, or approximately so. (such last runnings being variously known as wax tailings, still wax or gum). 40 Such arrangements are known and form no part of the present invention.

The shell a of said large tower below the flue jacket j is shown provided with a non-conducting jacket 15; so as to permit a separation of condensate before the vapors commence to be cooled by the air in the flue formed by jacket j , and the wall of shell a . The vapors pass from the crude oil still (not shown) through the upwardly inclined 45 vapor pipe 16 to the lower part of the shell a of said large tower. The residual vapors pass from the upper part of said large tower through the vapor pipe 17 to the lower part of the small tower (Fig. 2).

50 The residual vapors from the small tower of Fig. 2 would pass by pipe 18 to a water cooled condenser not shown. The condensate from said small tower is withdrawn through pipe 19 and can be collected as distillate or be returned to the oil distillation, as preferred.

With a crude oil still in the form of a horizontal cylinder 14½ feet in diameter and 47 feet in length, it is considered suitable to 55 use a large tower with a shell a seven feet in diameter and twenty three and a half feet in height, containing three deflectors f and three deflectors w and a small tower with a shell a four feet in diameter and 65 eleven feet in height, the vapor pipe 16 to

be twelve inches in diameter and the vapor pipe 17 to be ten inches in diameter. The annular passages g in the large tower may be say two inches in width between the rims f'' of deflectors f and the inclosing 70 shell a . The annular passages g in the smaller tower may be say three inches between the rims f'' of the deflectors and the and the inclosing shell a .

While the intention is, in distilling under 75 superatmospheric pressure, to hold the vapors under the still pressure when they are passing through the tower, they might, if so desired, be passed through the tower while held under atmospheric or other pressure 80 below that in the pressure still.

Modifications by addition, omission or otherwise can be made indefinitely in the subject-matter herein above described, so long as the substance is retained of any one 85 or more of the hereinafter written claims.

I claim as my invention or discovery:

1. In separating constituent hydrocarbons of petroleum vapors from each other, by a procedure wherein petroleum vapors evolved at temperatures above 90 600° F. have the form of a thin annular stream, divided into successive sections of greater length than thickness of stream while flowing over and in contact with the surface of 95 an air-cooled heat-conducting wall, the improvement which consists in abstracting heat from said thin stream of vapors by means of a confined and controlled stream of cooling air greater in thickness than the vapor 100 stream and equal in length to the combined lengths of a succession of said vapor stream sections, the said air stream flowing over and in contact with the opposite surface of said heat-conducting wall and becoming warmer 105 as it passes the successive sections, and in causing the so formed condensate to separate from the vapors between sections and to flow away without descending through lower sections of said vapor streams, substantially as described.

2. A condensing tower for separating constituent hydrocarbons of petroleum vapors from each other, which tower comprises (first) an elongated shell of heat-conducting 115 material having an inlet for vapors to be partially condensed and an outlet for residual vapors, (second) rimmed deflectors located inside said shell transversely to the tower axis at intervals between 120 said vapor inlet and vapor outlet and so constructed and arranged as to leave a succession of annular open-ended vapor passages of greater length than thickness between the deflector rims and the shell 125 wall, (third) an elongated jacket so constructed and arranged outside said shell as to form an air flue around said shell, that is greater in thickness than the said vapor passages, said air flue being open at its lower 1

- part for ingress of cooler air and at its upper part for egress of the warmed air, and extending over a succession of said vapor passages, and (fourth) means for controlling the flow of air through said flue, provision being made for inducing condensate, to separate from the vapors in the spaces between adjacent vapor passages and for causing the separated condensate to flow away without descending through lower vapor passages, substantially as described.
3. In separating constituent hydrocarbons of petroleum vapors from each other, by a procedure wherein petroleum vapors evolved at temperatures above 600° F. have the form of a thin annular stream, divided into successive sections of greater length than thickness of stream while flowing upwardly over and in contact with the surface of an cooled heat-conducting wall, the improvement which comprises, in combination, the three steps of (first) abstracting heat from said thin stream of vapors by means of a confined and controlled stream of cooling air, greater in thickness than the vapor stream and equal in length to the combined lengths of a succession of said vapor stream sections, the said air stream flowing over and in contact with the opposite surface of said heat-conducting wall and becoming warmer as it passes the successive sections, (second) separating condensate from the upwardly flowing vapor stream in the spaces between adjacent sections of said stream, partly by adhesion to two successive overlying surfaces located transversely to the vapor stream and inclined downwardly away from said heat-conducting wall, and partly by falling on an intermediate underlying surface of a not substantially greater area, so constructed and arranged as not to intercept condensate that drops from the lowest part of the surface above, and (third) causing the separated condensate to flow away without descending through lower sections of said vapor stream, the inclination of the overlying surfaces mentioned being sufficient to induce the adhering condensate to flow away from said heat-conducting wall beneath said surfaces while adhering thereto, substantially as described.
4. A condensing tower for separating constituent hydrocarbons of petroleum vapors from each other, which tower comprises (first) an elongated shell of heat-conducting material having an inlet below for vapors to be partially condensed and an outlet above for residual vapors, (second) deflectors in the form of funnel-like disks with upright peripheral rims located inside said shell transversely to the tower axis at intervals between said vapor inlet and vapor outlet and so constructed and arranged as to leave a succession of annular open-ended vapor passages of greater length than thickness between the deflector rims and the shell wall, (third) an elongated jacket greater in diameter than the said shell except at the top, where it is reduced to an opening smaller than the said shell in diameter, said jacket forming an open-ended air flue greater in thickness than the said vapor passages, surrounding said shell and located in part directly over the top thereof, and (fourth) a valve for the opening at the top of said jacket arranged by its adjustment to control the flow of air through said flue, provision being made for inducing condensate to separate from the vapors in the spaces between adjacent vapor passages and for causing the separated condensate to flow away without descending through lower vapor passages, substantially as described.
- In testimony whereof I affix my signature to this specification.

HENRY C. SMART.
